UNITED STATES PATENT OFFICE.

ARTHUR C. JACKSON, OF PHILADELPHIA, PENNSYLVANIA, ASSIGNOR TO MILLER LOCK COMPANY, OF PHILADELPHIA, PENNSYLVANIA, A CORPORATION OF PENNSYLVANIA.

DESIGN FOR A COMBINATION KNOB AND DIAL FOR A LOCK.

Application filed February 13, 1923. Serial No. 5,167. Term of patent 3½ years.

To all whom it may concern:

Be it known that I, ARTHUR C. JACKSON, a citizen of the United States, residing in Philadelphia, Pennsylvania, have invented a new, original, and ornamental Design for a Combination Knob and Dial for a Lock, of which the following is a specification, reference being had to the accompanying

drawing, forming part thereof, in which the figure is a perspective view of the combination lock dial illustrating my design.

I claim:

The ornamental design for a combination knob and dial for a lock, as shown.

ARTHUR C. JACKSON.
